To all whom it may concern:

Be it known that I, DAVID C. FRANK, a citizen of the United States, and a resident of the city of New York, borough of Manhattan, county and State of New York, United States of America, have invented a new, original and ornamental Design for Narrow Fabrics, of which the following is a specification, reference being had to the accompanying drawing, forming a part thereof, wherein—

The stripings are contrasted by color and width and by blocks of contrasted color substantially as indicated on the drawing.

The figure represents a plan view of my design as particularly adapted to a ribbon.

What I claim and desire to secure by Letters Patent, is:

The ornamental design for a narrow fabric substantially as shown and described.

DAVID C. FRANK.
